CLAIM

I claim the ornamental design for a bath basin safety cover, as shown and described.

DESCRIPTION

FIG. 1 is a top perspective view of the bath basin safety cover;

FIG. 2 is a bottom perspective view of the bath basin safety cover;

FIG. 3 is a bottom view of the bath basin safety cover;

FIG. 4 is a left side view of the bath basin safety cover;

FIG. 5 is a top view of the bath basin safety cover;

FIG. 6 is a right side view of the bath basin safety cover; and,

FIG. 7 is an end view of the bath basin safety cover.

The portions of the bath basin safety cover shown in broken lines form no part of the claimed design.
